BASEBALL GAME BOARD

Ferdinand Beierle, Detroit, Mich.

Application December 2, 1949, Serial No. 130,712

2 Claims. (Cl. 273—93)

1

This invention relates to toy baseball games of the type having a playing field or diamond on a game board in combination with players freely positioned on the board, and play indicating means also mounted on the board, and in particular the invention includes a game board having a diamond including a pitchers mound and home plate positioned thereon with players freely positioned on the board and actuated by traveling magnets on the under surface of the board and a plurality of spinning rollers actuated by a thumb button for indicating the different plays.

The purpose of this invention is to improve the usual toy baseball game by providing means positioned at one end of a game board having a playing field thereon for indicating the plays and also for advancing players freely mounted on the board from one position to another.

In the usual type of toy baseball games cards representing players are positioned over a spinner or other means are provided for indicating plays and the playing pieces are manually actuated. With this type of game board interest in the game is soon lost because the elements do not represent players and where cards are used the cards are lost and damaged. With this thought in mind this invention contemplates an improved game board having a representation of a playing field thereon with sufficient players to represent two teams provided in combination with the board and with means incorporated in the construction of the board whereby the players may be advanced from a point at one end of the board as plays are made.

The object of this invention is, therefore, to provide means for constructing a baseball game board whereby players may be advanced around a diamond indicated thereon without positive contact of the players with the advancing means and whereby means is provided for indicating substantially all plays included in a game of baseball.

Another object of the invention is to provide a baseball game board having indicating means mounted thereon with players freely positioned and adapted to travel around a playing field on the board in which means is provided for actuating a pitcher freely positioned on the board as a play is made.

A further object of the invention is to provide an improved baseball game board having players separated from the board and actuated by magnets incorporated in the board and also provided with play indicating means mounted on the board, which is of a simple and economical construction.

With these and other objects and advantages in view the invention embodies a game board having a baseball diamond indicated thereon with a plurality of rollers rotatably mounted in a

2

casing having windows therein on the board with play indicating indicia on the rollers and with means for actuating players, separate from the board, on the board.

5 Other features and advantages of the invention will appear from the following description taken in connection with the drawings wherein:

Figure 1 is a plan view of the baseball game board illustrating the relative positions of the parts.

Figure 2 is a side elevational view showing the board with players freely positioned thereon.

Figure 3 is a longitudinal section through the center of the game board with parts at the ends broken away.

Figure 4 is a sectional plan through the game board with the upper surface of the board removed and taken on line 4—4 of Figure 3.

10 Figure 5 is a detail showing a section of the play indicating cylinder of the game board with a play indicated thereon by dot and dash lines and arrows.

Figure 6 is a detail through the play indicating roller showing a spring associated with one of the sections thereof wherein the section rotates in a counterclockwise direction as the roller is actuated.

15 Figure 7 is a similar section showing a section of the roller that rotates in a clockwise direction as the roller is actuated.

Figure 8 is a cross section through the outer end of the game board taken on line 8—8 of Figure 1 illustrating folding wings at the sides of the board.

20 Figure 9 is a plan view showing a magnet operating spool positioned in the board and mounted to actuate the magnet carrying elements.

Figure 10 is an exploded view illustrating the play indicating cylinder sections with combinations of plays illustrated thereon.

25 Figure 11 is a detail illustrating one of the playing pieces.

Figure 12 is a detail illustrating the relative positions of the playing pieces and magnets with the magnets positioned in a track in the under surface of the board.

30 Figure 13 is a similar detail showing a section taken at right angles to that shown in Figure 12 showing the construction of one of the playing pieces.

Figure 14 is a detail illustrating one of the magnets for actuating the playing pieces.

35 Referring now to the drawings wherein like reference characters denote corresponding parts the improved baseball game board of this invention includes a panel 10 providing a playing field, a spool 11 rotatably mounted below the board and positioned to operate magnets 12, a winding spool 13, a shaft 14 actuated by a button 15 and on

which a plurality of rollers are mounted, and playing pieces 16 representing men or baseball players.

The board 10 is formed as illustrated in Figures 1, 2, and 8 with flanges 17 and 18 at the sides for suspending the board above a base 19, and with an operating panel 20 at one end and wings 21 and 22 hinged to the sides for extending the right and left fields of the diamond. The wing 21 is connected to the edge of the board 10 by a hinge 23 and the wing 22 is connected by a hinge 24. By this means the wings may be folded to flat positions on the board when not in use. The edges of the wings are provided with flanges 25 and 26, respectively for supporting the wings in the same plane as that of the upper surface of the board 10.

The spool 11 is rotatably mounted on a pin 27 of the base 19 and the upper flange 23 of the spool is provided with an extension 29 in which a pin 30 is positioned as shown in Figures 3 and 9.

The pin 30 of the spool 11 is positioned to receive a loop 31 of a connector 32 that extends from a continuous cord 33 on which the magnets 12 are attached as illustrated in Figure 4. The cord 33 is trained over pulleys 34 on a disc 35 that is carried by the board 10 and that is provided with a centrally disposed opening 36 which receives the upper end of the pin 27 whereby the disc 35 with the pulleys 34 is stationary and the cord 33 which slides around the pulleys is pulled by the connector 32.

The magnets 12 are attached to the cord 33 as illustrated in Figure 14 with slots 37 in the magnets positioned at right angles to the cord whereby the slots of the magnets extend transversely across the track 38 of the baseball diamond as the magnets travel around the diamond.

The magnets are actuated, therefore, by turning the spool 11 and the spool 11 is rotated by a cord 39 which extends therefrom to the winding spool 13 on the panel 20 with the cord extended through the end of the game board as illustrated in Figures 1 and 4. The spool 13 is rotatably mounted on a pin 40 and a knob 41 is provided on the upper surface by which the spool is rotated to wind the cord 39 thereon and as the cord is drawn from the spool 11 the spool 11 rotates to move players around the diamond or track on the game board. After a game is played the board 10 may be moved upwardly and the cord 39 rewound on the spool 11.

The panel 20 is provided with tongues 42 and 43 that extend through slots in a flange 44 at the end of the game board and the panel may also be provided with flanges 45 and 46, the end of which may also extend through slots in the end of the game board.

The shaft 14 is rotatably mounted in bearings 47 and 48 at the sides of the board and a plurality of cylindrical sections 49, 50, 51, 52, 53, 54, 55, and 56 are freely rotatable on the shaft and are adapted to spin as the button 15 is pressed downwardly. The button 15 is vertically slidable in a casing 57 positioned over the roller and the lower end is connected by a tape 58 to a pulley 59 which is keyed to the shaft 14. The button 15 is carried by the upper end of a stem 60 that is slidably mounted in a bearing 61 and to the lower end of which the tape 58 is attached.

Each of the roller sections 49 to 56, inclusive, is provided with a recess 62 and thin wire springs 63 and 64, respectively are positioned in these recesses with the springs 63 mounted in the shaft 14 through openings 65 and the springs 64,

through openings 66. The springs 63 are positioned as illustrated in Figure 6 with the ends or points 67 thereof in contact with the wall of the section around the recess whereby with the shaft 5 rotated in a counterclockwise direction the point 67, contacting the wall around the recess rotates the section of the roll in a counterclockwise direction, whereas the spring 64 permits the sections to remain stationary as the shaft is rotated 10 in a counterclockwise direction with downward movement of the button 15 and as the button returns in the upward movement the point 68 rotates the roll sections in a clockwise direction. With these springs oppositely positioned in the 15 recesses of the roller sections some sections will rotate in one direction and others in the opposite direction.

The windows 69 of the casing 57 are labeled, as 20 illustrated in Figure 1, and, with suitable indicia provided on the surfaces of the roll section, different plays may be indicated through the windows, and, as illustrated in Figure 5, the roller sections may stop to indicate that the pitcher threw the ball and the batter swings striking a 25 fly to center field for a single. By the same means the pitcher may throw a ball, the batter may strike out or hit a grounder, bunt or foul and the ball may go to either one of the players, and at the same time the device indicates whether 30 the batter is out or makes a single, double or triple, or comes all of the way around for a home run.

In the game of baseball each time a pitcher throws the ball a play is set up and pressing 35 downwardly of the button 15 represents a play in the game of baseball. To make the game realistic a magnet 70 is provided below the pitchers mound 71 and a slider 72, positioned below the board is connected by a cord 73 to an arm 74 extended from the shaft 14 whereby each time the shaft is actuated by the button 15 the slider 72 moves forward and a rubber band 75 extended around the magnet 70 and carried by a bearing or clip 76 holds the magnet outwardly. 40 This forward and backward movement of the magnet causes a pitcher 77 on the mound to turn slightly or at least move with a rocking movement. The magnets, therefore, actuate the pitcher as well as the players.

50 When a play is completed and set up through the windows of the casing 57, pointers 78, 79, and 80 may be moved by hand to indicate the ball, strike or an out and should the player arrive at first base the magnet 12, at that time positioned 55 below the home plate is moved to first base by turning the winding spool 13 which actuates the spool 11 that draws the magnet positioned at the home plate toward first base so that a player standing on the board follows the magnet and travels toward first base. Should the player strike a home run this action is continued and the player follows the magnet continuously around the diamond returning to the home plate. The player may stop at either base depending 60 upon the indicia showing through the windows of the casing 57.

The game board is also provided with foul lines 65 81 and 82 and areas 83 and 84 in which players may be stationed.

70 The playing pieces 16 are provided with metal bases 85 which are mounted on the lower end of the playing pieces by pins 86 that extend upwardly into the body of the playing piece to which the base is attached.

75 The stationary pulley 85' under the home plate

corner of the diamond is provided with a groove 86' through which the cord 73 extends and the under surface of the board 10 is provided with a track 87 in which the magnets 12 travel. A stop 88 is provided on the pulley 59 to limit the rotary movement thereof.

The recesses 62 in the roller sections are provided with split wire springs 89 which prevent the springs 63 and 64 working out of the recesses.

With the parts arranged in this manner the playing pieces may be divided into sets of nine indicating a team of nine players and the players of each team are preferably of the same color whereby players of the different teams are distinguished by the colors. In playing the game 15 the button 15 is pressed downwardly and the sections of the roller spin around stopping with certain indicia showing through the windows. From this indicia the player understands whether or not the man is out, or whether the ball is a strike, 20 ball, hit or the like, and with this information the play is executed as hereinbefore described. Playing is continued until three men of one team are out and then the players alternate with the players of the other team going to the bat. The 25 playing is continued until nine, or any suitable number of innings have been completed.

It will be understood that modifications may be made in the design and arrangement of the parts without departing from the spirit of the invention.

What is claimed is:

1. In a baseball game, the combination which comprises a horizontally disposed board having a baseball diamond with a home plate, the first, second, and third bases therein illustrated thereon, magnets corresponding with the bases and home plate of the diamond positioned against the under surface of the game board, means conveying the magnets around the diamond, a spool positioned below the magnet conveying means, means connecting the spool to the magnet conveying means, an operating panel extended beyond one end of the game board, a winding spool mounted on the panel and connected by a cord to 45 the spool below the magnet conveying means for actuating the said spool of the magnet conveying means, a plurality of playing pieces freely positioned on the game board, said playing pieces having bases of material having magnetic attraction whereby upon operating the magnet conveying means displaying pieces travel around the baseball diamond, and a longitudinally operating

magnet positioned in the center of the diamond for actuating a playing piece representing a pitcher.

2. In a baseball game, the combination which 5 comprises a horizontally disposed board having a baseball diamond with a home plate, and first, second, and third bases therein illustrated thereon, a roller having play indicating indicia on the surface thereof rotatably mounted on the board, a button positioned at one end of the roller for spinning the roller, magnets corresponding with the bases and home plate of the diamond positioned against the under surface of the game board, means conveying the magnets around the diamond, a spool positioned below the magnet conveying means, means connecting the spool to the magnet conveying means, an operating panel extended beyond one end of the game board, a winding spool mounted on the panel and connected by a cord to the spool below the magnet conveying means for actuating the said spool of the magnet conveying means, a casing having windows therein enclosing the roller, a plurality of players made of material having magnetic attraction adapted to be influenced by the magnets, an additional magnet positioned below the center of the diamond for actuating a player made of material having magnetic attraction representing a pitcher, and means actuating the magnet below the player representing the pitcher by the roller, and as the roller is actuated by the said button.

FERDINAND BEIERLE.
